FIG. 6.

INVENTOR.

HARRY E. OWEN

BY *Thomas L. Ryan*
ATTORNEY.

UNITED STATES PATENT OFFICE.

HARRY E. OWEN, OF MUNCIE, INDIANA.

LIGHT-SHADING DEVICE.

1,420,443.

Specification of Letters Patent. Patented June 20, 1922.

Application filed April 23, 1921. Serial No. 463,818.

To all whom it may concern:

Be it known that I, HARRY E. OWEN, a citizen of the United States, residing at Muncie, in the county of Delaware and State of Indiana, have invented certain new and useful Improvements in Light-Shading Devices, of which the following is a specification.

This invention relates to improvements in light-shading devices, and has for its purposes to provide a device capable of being easily installed, and which may readily be manipulated to shade or screen, in varying degree, the light, or the heat of the sun.

The invention is embodied in a light-shading device of construction and arrangement to be installed at the front of the automobile, the connections being adapted for its installation at the upper portion of the wind shield, and at position of easy access by the driver of the car.

Objects of the invention are to provide a device of the kind described which is economical of manufacture, dependable, and not liable to become deranged or to get out of repair.

The objects of my invention are accomplished by, and the invention is embodied in the new construction, combination and arrangement of parts described in the following specification, and illustrated in the accompanying drawings. The invention is defined in the appended claims.

In the drawings the several parts of the invention as they appear in the different views, are identified by suitable characters of reference.

Figure 1 is a front view of my improved light-shading device.

Figure 2 is a side view, in the direction indicated by the arrow 2 in Figure 1.

Figure 3 is an enlarged side view; portions of the device being shown in cross section.

Figure 4 is a view, in the direction indicated by the arrow 4 in Figure 3.

Figure 5 is a sectional view on the line 5-5 in Figure 4, and

Figure 6 is a cross section view taken on the line 6-6 in Figure 4.

This invention contemplates the arrangement of supports capable of being attached to the wind shield, a curtain arranged on a roller having its ends journaled in said sup-

ports, means carried by the supports and connected to the curtain and that are so ar-

ranged that the curtain is normally at lowered or unrolled position, and manually operable means to so function with the roller, that the curtain may be easily rolled up entirely, or may be rolled up only partially, and that the roller may be secured at different positions, the bottom edge of the curtain being retained at different desired heights accordingly.

The preferred form of construction and arrangement of the several combined parts, is that shown in the drawings, it being understood that minor changes may be made in the forms and details, without departing from the nature and spirit of the invention, or sacrificing any of its advantages.

The curtain roller A may be of metal tubing of suitable gauge and diameter as shown, and throughout its length are provided perforations to receive fasteners B that firmly secure the edge of the curtain C. The curtain is dimensioned in width to suit the width of wind-shield that forms a part of the automobile equipment, and is made of suitable fabric, such as canvas or leather cloth. The lower edge of the curtain has an open hem, in which is disposed a stiff bar or rod D. The rod D is preferably of tubular construction which while light in weight is of sufficient stiffness. At the ends of the roller A are secured heads which have integrally formed journals A¹ and A³. On the shouldered portion A³ of one of the heads, a grooved ring or wheel E is secured, and adjacent thereto is secured a circular ratchet F. Secured to the ends of the rod D, are journals D¹ that have integrally formed heads D².

Adapted to be secured at positions a spaced distance apart are the supports. Each support consists of a cast metal column G, near whose top is a transverse bore which constitutes a bearing for the journals A¹ and A³ of the roller. H designates a pawl whose tooth engages the ratchet F, and whose arm is of a downwardly curved form as shown in Figure 3. This pawl is pivoted on a stud I, and at the end of the arm is formed the eye H². The free end of the cable or cord J that is wound over and has secure connection in the groove of wheel E, is passed through the eye H² of the pawl arm H¹, and it may be provided with a handle or ball J¹.

The body portion of the support G is cylindrical in cross section, but at the lower

portion is of open form with parallel side walls G^2 that support a transverse pin K . The arm L journaled on the pin K , has an integrally formed grooved quadrant L^1 . A cable M has a flanged head M^1 . N designates a strong helical spring which occupies the bore of the support G and whose upper end bears against the underside of the head M^1 . The seat plug O (and through whose central bore, the cable M is free to move), is screwed to the position shown, and against its top bears the bottom of the spring N . A knot or washer M^2 on the bottom of the cable occupies a countersink in the lower side of the quadrant L^1 . A lug L^2 on the arm L has bearing against the edge of the wall G^2 when the arm is at extreme lower position. The headed studs or journals D^1 are retained in the open ends of the arms L and L by 20 cotter pins P .

A sheet metal housing Q having the upwardly turned rearward edge and having its frontal portion curved downwardly, constitutes a housing, by which the roller and 25 curtain when folded to the dotted line position, is shielded from the elements.

The preferred form for securing the supports G in position, are clamping pieces R whose forward portions grip the supports G and whose rearward portions grip the frame members 2 of the windshield, and are bound at tenacious contact with the said parts, by bolts R^1 .

The positions of the several parts, when the invention is at operative position with the curtain extended, are those shown in the drawing. The action of the spring N is to urge the arms L to lowered position, thereby maintaining a tension on the curtain 35 C , the turning of the roller A being checked by the pawl H . To raise the curtain, the operator pulls downwardly on the cord J causing the roller A to move rotatively, and which roller in such movement is checked, 40 and is prevented from reverse movement, by the pawl H . Thus, the curtain may be raised to the folded or "rolled up" position as shown by the dotted lines. To lower the curtain, a pull rearwardly of the cord J against the eye H^2 disengages the tooth of the pawl H from the ratchet F , permitting the arms L to assume a lower position, and the curtain being accordingly lowered. Repeated 45 operating of the pawl in the manner just described results in the further lowering of the curtain to the desired height. When thus lowered to the height desired the release by the operator, of the cord, permits 50

the pawl to remain at its engagement with the ratchet F , thus holding the roller A 55 against movement.

What is claimed, as my invention, and desired to be secured by Letters Patent, is—

1. A light shading device, comprising a roller, a grooved wheel secured thereto a 60 curtain secured to the roller, a rod to which the outer end of the curtain is secured, support members, fastening devices to maintain the support members at spaced distance apart, arms hinged to the support members 65 and having the outer ends connected loosely to the ends of the curtain rod, springs to urge the said arms to lowered position, a ratchet on the curtain roller, a pawl to engage the ratchet, a cord wound over the 70 grooved wheel, and an arm for the said pawl provided with an eye at its lower end, the said cord being passed through said eye, substantially as described.

2. A light shading device, comprising a 80 roller, a curtain secured to the roller, support members, arms hinged to the support members and having their ends connected to the lower ends of the curtain, extender 85 means to urge the said arms to lowered position, a ratchet on the curtain roller, a pawl to engage the ratchet, a downwardly disposed arm for the pawl having an eye at its lower end, and a cord wound on the 90 roller and being passed through the eye of said arm.

3. A light shading device, comprising a roller, a grooved wheel secured thereto, a curtain secured to the roller, a rod to which the outer end of the curtain is secured, support members, fastening devices to maintain the support members at spaced distance apart, a shelter housing carried by the support members at position above the roller, arms hinged to the support members and having their outer ends connected loosely to the ends of the curtain rod, a spring to urge the said arms to extended position, a ratchet on the curtain roller, a pawl to engage the ratchet, a downwardly disposed arm for the 105 pawl and having an eye at its lower end, and a cord wound on the grooved wheel and which is passed through the eye of said pawl arm, and which said cord is manually operable to retract the curtain roller, and is 110 also operable to disengage the pawl from the ratchet and at the same time permit the roller to move in the reverse direction.

In testimony whereof I affix my signature.

HARRY E. OWEN.
